(No Model.)

L. F. GRAMMES.
BOX NAILING MACHINE.

No. 409,145.

Patented Aug. 13, 1889.

UNITED STATES PATENT OFFICE.

LEWIS F. GRAMMES, OF ALLENTOWN, PENNSYLVANIA, ASSIGNOR OF ONE-HALF TO C. J. P. BITTNER, OF SAME PLACE.

BOX-NAILING MACHINE.

SPECIFICATION forming part of Letters Patent No. 409,145, dated August 13, 1889.

Application filed December 17, 1887. Serial No. 258,202. (No model.)

To all whom it may concern:

Be it known that I, LEWIS F. GRAMMES, a citizen of the United States, residing at Allentown, in the county of Lehigh, State of

5 Pennsylvania, have invented certain new and useful Improvements in Box-Nailing Machines, of which the following is a specification, reference being had therein to the accompanying drawings.

10 This invention has relation to box-nailing machines, and among the objects in view are to provide a picker attachment for the same adapted to select and conduct nails singly from the tumbling-box to the chuck and in 15 the path of the hammer, whereby they are driven into the object thereunder.

Other objects and advantages of the invention will hereinafter appear, and the novel features thereof will be particularly pointed 20 out in the claims.

Referring to the drawings, Figure 1 is a plan view of a portion of the attachment; and Fig. 2 a section on the line $x-x$ of Fig. 1, adjacent portions of the nailing-machine being 25 shown by dotted lines. Figs. 3 and 4 are details in plan showing the positions occupied by the picking-fingers during the operation of selecting a nail. Fig. 5 is a plan of one of the picking-plates, and Fig. 6 a similar view 30 of its companion. Fig. 7 is a partial rear view of the attachment, showing the gate employed for admitting a nail to the picking-fingers.

Like letters indicate like parts in all the 35 figures.

This attachment is especially designed to be used in connection with my invention, as illustrated in Patent No. 249,245, though I do not limit the same to an application to this 40 invention, but hold that it may be used in connection with any box-nailing machine to which it is applicable.

B represents an inclined table leading from the usual tumbling-box A, and supported in 45 any suitable manner upon the machine. A slot B' is formed in the table, the edges of which are provided with metal plates B², forming a way. The slots B' may be of any suitable number, as may also the picking 50 mechanism hereinafter described, said slots and mechanism being limited merely by the

number of drivers employed in the machine. I have herein shown but one slot and picking mechanism, deeming that sufficient to fully illustrate my invention.

55 The table B is provided with a circular recess B³ at the end of the slot B', which recess is centrally perforated at B⁷ for the reception of a screw B⁴, having a cylindrical body portion B⁵. A second perforation B⁶ is provided 60 intermediate the lower end of the way B' and the central perforation just mentioned.

Mounted within the circular recess B³ of the table and rotatably upon the body portion B⁵ of the screw B⁴ is a picker-plate C, having 65 central perforations C', a stud C², projecting from its upper face and near the edge thereof, a slotted extension C³, extending from its periphery and opposite long and short picking-fingers C⁴ C⁵, respectively, forming an eccentric slot terminating in an opening C⁶. A second plate D is also mounted upon the body portion B⁵ of the screw B⁴ and above the plate C, which plate D is formed with a central perforation D' for the reception of the screw B⁴, 70 a stop or shoulder D², and upwardly-projecting stud D³, and long and short oppositely-inclined picking-fingers D⁴ D⁵, respectively, which fingers are arranged opposite to similar fingers upon the plate C, so that when operated or oscillated in contrary directions the long fingers C⁴ D⁴ of the two plates are drawn 75 toward and thrown away from each other, as are also the short fingers D⁵ C⁵, thus opening and closing the opening C⁶ D⁶ of the two 80 plates.

Pivoted at one side of the inclined table B is a bar E, having a central longitudinal slot E', into which takes the stud D³ of the plate D, and a similar slot E², into which takes the 90 stud C² of the plate C. A coiled retracting-spring F is connected with the stud C² and to a stud or screw F', formed at that side of the table B opposite to the pivotal connection of the bar or lever E.

95 Mounted in suitable brackets B⁸, projecting forwardly from the table B, which brackets are slotted, are sliding bars G G', having upon their upper faces stops G². While only one bracket is shown, it will of course be understood that in practice there are two, one at each end of the table. A retracting-spring G³ (see

dotted lines, Fig. 1) connects the bar G' with the bracket B^8 , so that the stop G^2 thereof is normally held in contact with the inner side of said bracket.

5 Mounted in the slot C^3 of the extension of the plate C is a set-screw H , which is provided with a boss H' at its lower end, adapted to come into contact with and be actuated by one or the other of the bars G and G' in accordance with its location in the slot C^3 through the medium of the stops G^2 on said bars.

A space-block B^{11} , having an opening B^9 , registering with the opening B^6 in the table B , is provided at the front edge of said table and depends therefrom, which block is provided with a horizontal slot B^{10} passing therethrough, through which passes an arm G^4 , the opposite end of which is rigid with the bar G' . A gate 15 I is pivoted, as at I' , upon the rear face of said space-block B^{11} , and is formed with a slot I^2 , into which the end of the arm G^4 takes. Leading from the lower end of the opening B^9 in the block B^{11} to a chuck J in the nailing-20 machine is a throat K , which conducts the nails after being separated by the picker-plates C and D down to and within said chuck J and in the path of the hammer or plunger L , these parts being shown in dotted lines, 25 Fig. 2.

The operation of the machine is as follows: The tumbling-box A , it will be understood, is agitated by suitable mechanism, so that the nails therein pass into the slot B' of the inclined table B , the heads of the nails Z resting upon the flanges or plates B^2 at each side of said slot, so that the slot becomes completely filled with nails arranged in consecutive order. The machine being put in operation, suitable cams $D^9 D^{10}$, or other mechanism usually provided therein, first come in contact with and operate the bar G' , which, through the medium of its arm G^4 , actuates or oscillates the pivoted gate I , throwing the same to one side and permitting the first of the series 40 of nails to pass down the slot B' into contact with the forward or longer fingers $C^4 D^4$ of the plates C and D , which fingers when not actuated remain in a closed or lapped position. 45 As the gate opens and the first nail of the series is permitted to come in contact with said fingers, (see Fig. 3,) the bar G is, by suitable cams or other mechanism, pushed forward in its bearings and carries with it the plate C , 50 which oscillates upon the bolt B^4 . This movement of the plate C also oscillates the bar E , the end of which is loosely connected with the stud C^2 upon said plate. Now as the plate C and the bar E are swung upon their pivots, 55 said bar having the intermediate loose connection with the upper plate D , said upper plate D is moved in a contrary direction, so that the longer fingers C^4 and D^4 of the respective plates are withdrawn from each other, and the shorter fingers $C^5 D^5$, being oppositely arranged, are thrown toward each other. This withdrawing or opening of the

longer fingers permits the nail to come in contact with said shorter fingers. By this time the bar G and the plate C will have reached the limit of their oscillation in one direction, and the position of the two plates will be as clearly shown in Fig. 4. The cam or other pressure against the bar G having been removed, the retracting-spring F will bring the parts back to their normal positions, which are shown in Figs. 1 and 3. It is therefore plain that in this return movement the operation just described will be reversed—that is, the shorter fingers will first open or part, permitting the nail resting thereagainst to fall through the opening $C^6 D^6$ into the opening B^9 , down the throat K , and into the chuck J , where it is driven by the hammer or driver L . As the shorter fingers open, the longer fingers close, and the operation is repeated. Prior to the movement of the picker-operating bar G , or it may be at any time previous to the time when said bar reaches a point at which the longer fingers $C^4 D^4$ open, the gate-bar G' is operated by any suitable cam or other mechanism. In its movement the gate is oscillated from over the opening B^9 , so as to admit of a single nail passing up against the longer fingers of the picker-plates. As soon as this is accomplished, the cam or other pressure at the end of the bar G' is removed and the bar and gate are drawn to their respective positions by means of the retracting-spring G^3 . (See dotted lines, Fig. 1.) As the gate is brought to its return or normal position, it separates and passes in between the advance nail and the remainder of the series, thus preventing the admission of more than one nail at a single operation of the picker-plate.

The bar G is, by suitable mechanism—such as the well-known cam wiping against its end—operated every second stroke, while bar G' operates at every stroke, or G may be actuated at the second, third, or fourth stroke, while G' operates every stroke. The object of this is to nail bottoms or tops of boxes where it may require two nails at the sides and four or six at the ends. For instance, two nails are to be driven into the sides of a box and four nails into the ends thereof. To do this, bar G' is set or connected with two picker mechanisms, so as to drop two nails at every stroke, and G is set connected with two or more pickers, so as to drop two nails at every other stroke. Therefore, when the side is presented to be nailed G' drops its two nails and they are driven, while G drops none. The box is then turned and the end is presented, when both G' and G drop two nails each and the four are driven. At the next stroke the opposite side of the box is presented, and bar G' drops two nails, as required, and G drops none. The opposite end is then presented, and with this stroke bars $G' G$ drop two nails each, and the four are driven.

The importance of this improvement is

readily apparent, as it saves a great deal of adjustment in changing for the dropping of different numbers of nails at every alternate stroke, all the adjustment required being to 5 slide the thumb-screw H in its slot C³, so that its lower end will be thrown in the path of one or both of the stops G² on the sliding bars G G'.

Having described my invention and its operation, what I claim is—

1. A picker attachment for box-nailing machines, comprising an inclined slotted table, duplicate picker-plates mounted at the end of said table and for relatively-opposite oscillation, and mechanism for oscillating the same, substantially as specified. 15

2. The combination, with a nailing-machine, of a picker attachment comprising an inclined table having a slot and duplicate picking-plates provided with picking-fingers and nail-passages and pivoted and arranged one upon the other at the end of said slot, and mechanism for oscillating said plates in relatively-opposite directions, substantially as 25 specified.

3. The combination, in a nailing-machine, of a picker attachment comprising an inclined table having a slot, pivoted nail-picking plates mounted one upon the other at the end of 30 said slot and provided with picking-fingers and nail-passages, and mechanism for oscillating said plates in contrary directions, substantially as specified.

4. In a box-nailing machine, the combination of a picker attachment, comprising a slotted inclined table having picker-plates provided with picking-fingers pivoted thereon, mechanism for operating the same in contrary directions, a gate, and gate-operating 40 mechanism for presenting nails singly to said fingers, substantially as specified.

5. The combination, in a box-nailing machine, of an inclined table having a slot with pivoted picking-plates mounted one upon the 45 other and provided with oppositely-arranged picking-fingers, and with a locking-bar connecting said plates and retaining the same in a locked or closed position, substantially as specified.

50 6. In a box-nailing machine, the combination of an inclined slotted table, picking-plates mounted at the end of said table, a pivoted gate mounted in rear of said plates, and mechanism, substantially as shown and 55 described, for operating said pivoted gate in advance of the operation of said plates, substantially as specified.

7. The combination of a box-nailing machine, with a picking attachment comprising 60 an inclined table, slotted and provided with nail-picking plates having studs projecting

therefrom, and a bar pivoted to the table and slotted for the reception of the studs, whereby when one of said plates is oscillated in one direction its companion is oscillated in an opposite direction, substantially as specified. 65

8. In a picker attachment for box-nailing machines, the combination of a slotted inclined table, with pivoted picker-plates mounted one upon the other at the end of said slot 70 and provided with oppositely-disposed long and short picking-fingers and with studs, and a plate-operating bar slotted to receive said studs, substantially as specified.

9. In a box-nailing machine, the combination of an inclined table having a slot and provided with pivoted operatively-connected picking-plates having picking-fingers, one of said plates having a slotted extension, with an adjustable bolt mounted in said slot, and 80 oscillating bars mounted in brackets below the same and provided with lugs for coming in contact with and operating said bolt, substantially as specified. 75

10. In a box-nailing machine, the combination of an inclined table having picking-plates pivoted at the end thereof, and having a gate pivoted in rear of said plates, with oscillating bars, one of which operates said plates and the other the gate, substantially as specified. 85

11. The combination of the inclined table B, having the slot B', with the plates C and D, pivoted, as at D⁴, thereon and formed with the long and short fingers C⁴ C⁵ and D⁴ D⁵, 95 and having the openings C' C⁶ and D' D⁶, substantially as specified.

12. The combination of the table B, having the slot D', and the plates C and D, pivoted thereon, with the bar E, slotted as at E' E² 100 and mounted on said plate, and the spring F, substantially as specified.

13. The combination of the inclined table B, slotted as at B', and the plates C and D, pivoted as at B⁴ at the end of said slots, the 105 bolt H, mounted in the plate C, and the bar G', having the lug G² and spring G³, substantially as specified.

14. The combination of the inclined table B, slotted and provided with the pivoted plates C and D, the bar E, connecting the same with the gate I, pivoted as at I', slotted as at I², and the bars G and G', the latter having arm G⁴ for operating said gate, substantially as specified. 110

In testimony whereof I affix my signature in presence of two witnesses. 115

LEWIS F. GRAMMES.
